United States Patent Office

Des. 200,475
Patented Mar. 2, 1965

200,475

CLOTHES BUREAU

Martin E. Fortson, 1760 9th St., Manhattan Beach, Calif.

Filed June 1, 1964, Ser. No. 80,236

Term of patent 14 years

(Cl. D33—6)

The sole figure is a perspective view of the clothes bureau.

The interior of the side not shown is the same as the interior of the side shown while all undisclosed outer surfaces of the cabinet are plain and unornamented.

I claim:

The ornamental design for a clothes bureau, as shown and described.
